[57]

ABSTRACT

A reed switch cartridge is attached for operation by an oil tight switch actuator and is interchangeable with conventional switch cartridges. Two embodiments are shown and each includes a pair of reed switches which are positioned in switch chambers located on opposite sides of a plunger. A magnet carried by the plunger is polarized in the direction of plunger motion and generates a concentrated magnetic field at each of its ends. By operating the reed switches off the ends of the magnet a minimum amount of space is required for the switch-magnet combinations and changes in "pick-up" and "drop-out" points are minimized despite possible variations in magnet length or flux density. Means including clips are shown for adjusting the position of each reed switch and for thereby adjusting their initial pick-up and drop-out points.

REED SWITCH CARTRIDGE

BACKGROUND OF THE INVENTION

The invention relates to control switches, and more particularly, to switches of the rotary selector and pushbutton type which are commonly attached to the enclosure of such electrical equipment as motor starters, motor speed control circuits, and numerical control directors.

With the increased use of low voltage logic circuits at the input to electrical equipment, the demand for switches containing hermetically sealed, magnetically operable contacts, has increased dramatically. Such a switch, commonly referred to as a reed switch, is illustrated in U.S. Pat. No. 3,243,544, issued to J.C. Mayer on Mar. 29, 1966.

There are numerous commercially available oil-tight switches which contain Ser. No. 275,602 filed July 27, 1972 and entitled "Switch Mounting Structure", such switches include an actuator section of either the pushbutton or rotary selector type, and a contact block section which contains one or more switch cartridges. The switch cartridges are modular in construction, that is, they can be easily removed from the actuator section and replaced with other similar cartridges. In addition to having similar physical shapes and dimensions, each cartridge includes a plunger which extends into the actuator section of the switch and is operated by the mechanism therein to open and close one or more switch contacts in the cartridge. To provide a truly module switch cartridge, not only must the shape and dimensions of the switch cartridge be compatible, but a uniform plunger stroke must also be specified.

To provide a reed switch cartridge which is truly interchangeable with conventional switch cartridges, its shape, size and plunger stroke must be constrained in order to operate properly with commercially available switch actuators. The limited cartridge size and short and precise plunger stroke requirements associated with such switch actuators has heretofore proven to be a difficult constraint on the design of magnetically operated reed switch cartridges.

SUMMARY OF THE INVENTION

The present invention relates to a means of operating reed switches, and more specifically to a reed switch cartridge which is compatible with actuators used to operate conventional switches. The reed switch cartridge includes a frame that defines a switch chamber, a plunger slidably retained to the frame for translational motion along a central axis located adjacent to the switch chamber, a reed switch located in the switch chamber with its lengthwise dimension oriented substantially parallel to the central axis, and a magnet having a lengthwise dimension and a lateral dimension, which magnet is polarized along its lateral dimension and which is connected to the plunger with its lengthwise dimension oriented perpendicular to the central axis. A high energy ferrite magnet is used and the magnetic field which it generates is concentrated at its end positioned immediately adjacent the reed switch. Operation of the reed switch is thus accomplished in a minimum amount of space and the pick-up and drop-out points are precisely defined with respect to the leading edge of the magnet.

A general object of the invention is to provide a reed switch cartridge which is compatible with existing

switch actuators. By operating the reed switch "off the end" of a high energy magnet, the pick-up and drop-out points are made compatible with the plunger stroke requirements of existing switch actuators. Two reed switches may be operated in this manner, one off each end of the magnet.

A more specific object of the invention is to provide a reed switch cartridge in which either normally open or normally closed operation can be obtained. An offset gap reed switch is used, and by orienting the switch in the switch chamber in one direction a normally open operation is obtained. By orienting it in the opposite direction, a normally closed operation is obtained.

Another object of the invention is to provide a reed switch cartridge which is easily assembled and adjusted. The reed switches are retained to the cartridge frame by means of clips which allow adjustment of their position along an axis parallel to the central axis. Despite variations in magnet strength and reed switch operating characteristics, the position of the switches may be adjusted to "pick up" and "drop out" at the desired plunger position. Once the desired position is established, the reed switches are bonded in place.

The foregoing and other objects and advantages of the invention will appear from the following drawings which form a part hereof and which show by way of illustration two preferred embodiments of the invention. Such embodiments do not necessarily represent the full scope of the invention, and reference is made to the claims herein for interpreting the breadth of the invention.

BRIEF DESCRIPTION OF THE DRAWINGS

FIG. 1 is a view in cross section of the reed switch cartridge connected to a pushbutton type switch actuator,

FIG. 2 is a view in cross section of the switch of FIG. 1 taken along the plane 2-2,

FIG. 3 is a perspective view of the plunger and magnet which forms a part of the reed switch cartridge of FIG. 1,

FIG. 4 is a plan view of a selector switch containing a second embodiment of the invention,

FIG. 5 is a perspective view of one of the two reed switch cartridges contained in the selector switch of FIG. 4,

FIG. 6 is a plan view with parts cut away of the reed switch cartridge of FIG. 5, and

FIG. 7 is a schematic drawing of the magnet which is used in both embodiments of the invention.

DESCRIPTION OF THE PREFERRED EMBODIMENTS

Referring to FIG. 1, an oil-tight switch includes an actuator 1 and a contact block 2. The actuator 1 includes a pushbutton mechanism 3 which is connected for reciprocating motion in a central opening 4 of an actuator sleeve 5. The actuator 1 also includes a rectangular bearing plate 6 which is integrally formed to the actuator sleeve 5 and which extends radially outward therefrom to form a clamping surface 7. A set of four rubber gaskets 8 are disposed around the actuator sleeve 5 and positioned between the clamping surface 7 and the back surface of a mounting wall 9. The actuator sleeve 5 extends through an opening in the mounting wall 9 and a cover 10 is disposed around its forward end to enclose the pushbutton mechanism 3 and fasten

the actuator sleeve 5 to the mounting wall 9. For a detailed description of the actuator section 1 and particularly the manner in which it is attached to the mounting wall 9, reference is made to a copending patent application Ser. No. 270,420, filed July 10, 1972 and entitled "Switch Mounting Structure".

The contact block 2 is attached to the actuator 1 by means of four bolts (not shown in the drawings) which extend through the rectangular bearing plate 6 into threaded openings formed in the contact block framework 11. Securely fastened to the framework 11 is a switch cartridge which includes a frame 12 formed from a molded polyphenylene oxide plastic to define a pair of switch chambers 13a and 13b. The frame 12 includes a bottom wall 14, a pair of side walls 15a and 15b which extend upward from opposing edges of the bottom wall 14, and a front wall 16 which extends upward from the bottom wall 14 to join the forward ends of the side walls 15a and 15b. Disposed along the back edge of the bottom wall 14, and joining the back end of the side walls 15a and 15b are two sets of terminal chambers 17 and 18, one set associated with each switch chamber 13a and 13b.

The first set of terminal chambers 17 is defined by three integrally formed walls; an outside wall 19a which extends parallel to the side wall 15a but is disposed laterally outward therefrom, a partition 20a disposed laterally inward from the outside wall 19a, and an interior wall 22a disposed laterally inward from the partition 20a and extending in a direction parallel thereto to define a second terminal chamber 23a. The second terminal chamber set 18 is a mirror image of the terminal chamber set 17 and includes an outside wall 19b, a partition 20b and an interior wall 22b which define a third terminal chamber 21b and a fourth terminal chamber 23b. A set of four brass terminals 24-27 are fastened to the cartridge bottom wall 14 and located in the respective lug chambers 21a, 23a, 23b and 21b.

The switch cartridge is symmetrical about a central, longitudinal axis 28 which extends rearward through a central opening 29 in the front wall 16, between the switch chambers 13a and 13b, and between the terminal chamber sets 17 and 18. A plunger 30 is disposed along the central axis 28 and is slidably retained to operate along the central axis 28 by two sets of opposing retainer walls 31a and 31b. The retainer walls 31a and 31b are integrally formed to, and extend upward from, the bottom wall 14.

Referring to FIGS. 1 and 3, the plunger 30 includes a substantially rectangular-shaped magnet carrier portion 32 and an integrally formed operating end 33. The magnet carrier 32 is slidably retained between the retainer walls 31a and 31b and the operating end 33 extends from its forward end, through the central opening 29 in the front wall 16, and into the actuator section 1. The plunger 30 is biased in a forward, or unactuated position, by a bias spring 34 which is disposed between the back end of the magnet carrier 32 and a web 35 which bridges between the interior walls 22a and 22b. The plunger 30 is formed of molded acetal plastic and the magnet carrier portion 32 has a pair of slots 36 which are formed in opposing walls thereof and which extend from its back end, forward approximately two thirds of its length. A pair of opposing fingers 37 are formed along the edges of each slot 36, and each finger 36 is formed a flex inward towards one another to provide a slight constriction in the width of each slot 36

near its forward end. A rectangular-shaped magnet 38 is inserted into the slots 36 and is wedged between the fingers 37 which retain it to the carrier 32. The magnet 38 is a high energy magnet made from a ferrite material designed "M-5" which is commercially available from the Allen-Bradley Company. The magnet 38 has a residual flux density of approximately 3,800 gauss and a coercive force of approximately 2,500 oersteds.

Referring to FIGS. 1 and 7, the magnet 38 has a longitudinal dimension which is co-linear with an axis 39, and lateral dimensions which are co-linear with orthogonal axes 40 and 41. The magnet 38 is polarized in the direction of the orthogonal axis 40, or in other words along one of its lateral dimensions, and the resulting field is concentrated at each of its ends as indicated by the dashed lines 42 and 43. The magnet 38 is positioned in the switch cartridge with its lengthwise axis 39 perpendicular to the central axis 28 of the switch cartridge. The ends of the magnet 38 thus extend laterally away from the central axis 28 and are located immediately adjacent the switch chambers 13a and 13b. As a result, when the plunger 30 is operated, the magnet 38 is translated along the central axis 28 and the concentrated magnetic field at each of its ends is moved along the length of the switch chambers 13a and 13b.

Located in the respective switch chambers 13a and 13b are a pair of reed switches 44 and 45. The reed switches 44 and 45 are commercially available miniature offset-gap switches having an ampere-turn pick-up ranging from 25 to 40. The first reed switch 44 is connected to the switch cartridge by a pair of molded polycarbonate plastic clips 46 and 47 which are rigidly fastened to and extend upward from the bottom wall 14 of the frame 12. The switch leads are snapped into a slot formed in the top surface of each of the clips 46 and 47, and the reed switch 44 is thus slidably retained to the switch cartridge. An adjustment opening 48 is formed in the forward wall 16 of the frame 12 immediately forward of the reed switch 44, and by inserting a tool through this opening, the longitudinal position of the reed switch 44 can be adjusted after the cartridge is completely assembled. The second reed switch 45 is similarly mounted to the frame 12 by a pair of clips 49 and 50, and a second adjustment opening 51 is formed in the front wall 16 immediately forward of it.

The leads on the reed switch 44 are connected to the respective terminals 24 and 25 at the back end of the cartridge by a first conductor 52 and a second conductor 53. The conductors 52 and 53 are spot welded to the leads on the reed switch 44 and the terminals 24 and 25. A divider wall 54 is integrally formed to the bottom wall 14 and is located within the switch chamber 13a to separate and thus prevent the conductors 52 and 53 from making contact with one another. Similarly, the leads on the second reed switch 45 are connected through respective conductors 55 and 56 to the lugs 27 and 26, and a divider wall 57 is formed in the switch chamber 13b between them.

Referring to FIG. 1, the first reed switch 44 is positioned in the switch cartridge with its offset gap located toward the forward end of the cartridge. On the other hand, the second reed switch 45 is oriented with its offset gap toward the back end of the cartridge. As a result, the reed switch 44 operates as a normally closed switch and the reed switch 45 operates as a normally open switch. The plunger 30 is translated from its unactuated position shown in FIG. 1 by depressing the push-

button mechanism 3 against the operating end 33 of the plunger 30. The plunger 30 is translated one-quarter inch to an actuated position in which the bias spring 34 is completely compressed. In this actuated position, the concentrated magnetic field at each end of the magnet 38 is removed from the vicinity of the gap in the first reed switch 44 and into vicinity of the gap in the second reed switch 45. The specific points at which the switches 44 and 45 drop out and pick up vary considerably, depending primarily upon the particular magnet and reed switch chosen. Uniformity of operating characteristics is obtained, however, by adjusting the longitudinal position of the reed switches 44 and 45 through the adjusting openings 48 and 51. Once their positions are established the reed switches 44 and 45 are secured in place with a drop of adhesive on the clips 46 and 47.

In the preferred embodiment of the invention shown in FIGS. 1-3, the position of the normally closed reed switch 44 is adjusted to open after 0.05 inches of plunger travel from its unactuated position. The position of the normally open reed switch 45 is adjusted to close at a plunger position of 0.16 inches from the unactuated position. On the return motion of the plunger 30, the normally open switch 45 drops out when the plunger is approximately 0.135 inches from the unactuated position and the normally closed switch 44 picks up at approximately 0.025 inches from the unactuated position. A differential of approximately 0.025 inches is thus obtained between the pick-up and drop-out points of each reed switch 44 and 45. This differential minimizes the possibility of inadvertently opening and closing the switch during plunger travel. Although a normally open and normally closed pushbutton switching function is performed by the embodiment shown in FIGS. 1-3, it should be apparent to those skilled in the art that a variety of switching functions can be provided merely by reversing the orientation of one or both of the reed switches 44 and 45.

The second embodiment of the invention shown in FIGS. 4-6 is applied to a selector type switch actuator mechanism. The shape and physical dimensions of the cartridge differ from that shown and described above, however, the principles of operation are the same and this second embodiment is intended to illustrate the application of the invention to a different commercially available switch actuator. Referring to FIG. 4, the selector switch includes a selector switch actuator 60 and a contact block 61. The contact block is comprised of two reed switch cartridges. The switch actuator 60 includes a knob 62, which when rotated, operates a cam (not shown in the drawings) contained in a cylindrical body portion 64 of the switch. Rotation of the cam translates a pair of cam follower elements (also contained within the body portion 64) along a central switch axis 65 to operate the contacts in the contact block 61. For a more detailed description of the structure and operation of the switch actuator 60, reference is made to the copending patent application Ser. No. 286,531, filed Sept. 5, 1972, and entitled "Oil-Tight Selector Switch".

The contact block 61 is comprised of two reed switch cartridges, one of which cartridges 66 is shown in the drawings. The cartridge 66 includes a frame 67 which is formed of molded phenolic plastic, and includes polycarbonate plastic cover 68 which has a pair of opposing up-turned end pieces 69 and 70. Four openings in the cover 68 allow two sets of terminals 71a, b and

72a, b to extend upward through the cover 68. Threaded openings in each terminal 71a, b and 72a, b receive a screw 73 and attached wire clamp 74.

Referring to FIG. 5 in which the cover 68 is removed from the frame 67, a plunger 75 formed from molded acetal plastic and having a generally rectangular shape is slidably retained to the frame 67 for translational movement in a channel 76 located in the plane of the central switch axis 65. A bias spring 77 is positioned in the channel between the back end of the plunger 75 and an integrally formed back wall 78. A pair of keys 79 and 80 are formed on opposing sides of the plunger 75 and a keyway 81 and 82 is formed along each side of the channel 76 to receive the respective keys 79 and 80 and to provide limits on the translational motion of the plunger 75. An operating head 83 is formed on the forward end of the plunger 75 and communicates with one cam follower element in the switch actuator section 60 through an opening 84 at the forward end of the channel 76. A magnet 85 is inserted through an opening in the plunger 75 in a manner similar to that shown in FIG. 3 and described above. The magnet 85 is made of a ferrite material (M-5) and is identical to the magnet 38 shown in FIG. 7 and described above. It includes a longitudinal dimension which is substantially larger than its lateral dimensions and it is polarized in the direction of the central axis 65.

The ends of the magnet 85 extend laterally outward a short distance from the plunger 75 and into switch chambers 86 and 87 formed in the frame 67 along each side of the channel 76. A hermetically sealed reed switch 88 is located in the switch chamber 86 and connected to the frame 67 by a pair of clips 89 and 90. The base of each clip 89 and 90 is firmly attached to the frame 67 and the two leads of the reed switch 88 are slidably retained in slots 91 and 92 formed in the top of each. A second reed switch 93 located in the second switch chamber 87 is similarly attached to the frame 67 by a pair of clips 94 and 95. A pair of conductors 96 and 97 connect the leads of the first reed switch 88 to the respective terminals 71a and 71b, and a pair of conductors 98 and 99 connect the leads of the second reed switch 93 to the respective terminals 72a and 72b.

The reed switches 88 and 93 are positioned in the respective switch chambers 86 and 87 with their lengthwise dimension parallel to the central axis 65. The body portion of each reed switch 88 and 93 is positioned immediately adjacent one of the ends of the magnet 85 and the offset gap 100 and 101 in each is oriented towards the back of the switch cartridge. The end of one lead on the first reed switch 88 extends into a forward adjustment opening 102 in the frame 67 and the end of its other lead extends through a back adjustment opening 103. Similarly, the leads of the second switch 93 extend into a forward adjustment opening 104 and a back adjustment opening 105 to allow adjustment of the longitudinal position of the switch 93 after the cartridge 66 is assembled. After the longitudinal position of each reed switch 88 and 93 has been adjusted to provide the desired pull-in and drop-out points, an adhesive is placed in the slot of the clips 90 and 91 to securely fasten the reed switches 88 and 93 to the frame 67.

With a relatively short plunger stroke (0.250 inches) the reed switches 88 and 93 are opened and closed by the magnetic field generated at each end of the magnet 85. A number of factors contribute to the shortened plunger stroke. These include the relatively small lat-

eral dimension, or width, of the magnet 85(0.130 inches) as compared to the length of the reed switch body (0.520 inches), and the operation of the reed switch off the end of the magnet 85. The magnetic field is concentrated at the ends of the magnet 85 to provide a high gradient which results in large changes in magnetic flux at the switch gaps 100 and 101 with a relatively short plunger stroke. Sufficient flux is provided to operate the switches by using a high energy ferrite magnet that is polarized in the direction of the central axis 65. As in the pushbutton embodiment shown in FIGS. 1-3, a variety of switching functions can be provided merely by reversing the orientation of one or both of the reed switches 88 and 93.

Two embodiments of the invented reed switch cartridge have been described and illustrated and it should be apparent that either can be used with pushbutton or selector switch actuators. In each embodiment, a magnet is translated along a switch axis by a plunger and one or more reed switches are positioned along the ends of the magnet. A number of factors contribute to the compact design of both embodiments of the invention. These include a small switch body size, operating the switch off the end of the magnet, and a relatively small lateral dimension or thickness of the magnet. As a result, the reed switches need not be offset along the central switch axis to provide a reasonable differential, and the longitudinal dimensions of the switch cartridge are minimized.

I claim:

1. In a switch including a switch actuator section which is operable to translate a plunger along a central switch axis, a reed switch cartridge comprising:
 a frame that defines a switch chamber;
 a plunger slidably retained to the frame for translational motion along the central switch axis and being disposed adjacent said switch chamber;
 a reed switch connected to said frame and positioned within said switch chamber with its lengthwise dimension oriented substantially parallel to the central switch axis; and
 a magnet connected to said plunger, said magnet having a lengthwise dimension and a lateral dimension substantially less than said lengthwise dimension said magnet being oriented with its lengthwise dimension substantially perpendicular to said central switch axis, and said magnet being polarized along its lateral dimension;
 wherein operation of said switch actuator section translates said plunger and attached magnet to operate said reed switch.

2. The reed switch cartridge as recited in claim 1

wherein said magnet has a pair of lateral dimensions which define two ends and in which said reed switch is positioned in said switch chamber immediately adjacent one of said magnet ends.

3. The reed switch cartridge as recited in claim 2 in which said magnet is polarized in the direction of said central switch axis.

4. The reed switch as recited in claim 3 in which a second switch chamber is formed in said frame and a second reed switch is contained in said second switch chamber to operate off the second end of said magnet.

5. The reed switch cartridge as recited in claim 3 in which the lateral dimension of said magnet in the direction of said central switch axis is less than one third the length dimension of said reed switch body.

6. The reed switch cartridge as recited in claim 3 in which said plunger is operated between an unactuated and actuated position and in which the lateral dimension of said magnet in the direction of said central switch axis is less than one half the plunger stroke.

7. The reed switch cartridge as recited in claim 6 in which said magnet is formed from a ferrite material.

8. The reed switch cartridge as recited in claim 1 in which said reed switch is connected to said frame by a pair of clips which allow the position of the reed switch to be adjusted in the direction of the central switch axis.

9. The reed switch cartridge as recited in claim 8 in which said reed switch includes a pair of leads which extend from its ends in the direction of the central switch axis, in which said clips are rigidly attached to said frame, and in which said reed switch leads are slidably retained in slots formed in said clips.

10. The reed switch cartridge as recited in claim 9 in which an adjustment opening is formed in said frame in alignment with one of said reed switch leads.

11. The reed switch cartridge as recited in claim 1 in which said reed switch has an offset gap and in which it may be positioned in said switch chamber in one direction to obtain a normally open mode of operation, or it may be positioned in the reverse direction to obtain a normally closed mode of operation.

12. The reed switch cartridge as recited in claim 1 in which said frame defines a second switch chamber adjacent said plunger and a second reed switch is connected to said frame and positioned in said second switch chamber with its lengthwise dimension oriented substantially parallel to the central switch axis, and wherein said first and second reed switches are in substantial alignment with one another along the central switch axis.
